UNITED STATES PATENT OFFICE.

ELEAZER KEMPSHALL, OF SHARON, ASSIGNOR TO THEOPHILUS KING,
TRUSTEE, OF BOSTON, MASSACHUSETTS.

EYELET.

SPECIFICATION forming part of Letters Patent No. 548,558, dated October 22, 1895.

Application filed August 10, 1895. Serial No. 558,810. (No model.)

To all whom it may concern:

Be it known that I, ELEAZER KEMPSHALL, of Sharon, in the county of Norfolk and State of Massachusetts, have invented certain new and useful Improvements in Eyelets, of which the following is a specification.

This invention relates to eyelets which are coated at their outer ends with a plastic pyroxylene composition or its equivalent.

10 The invention has for its object to provide an improved construction of eyelet whereby the plastic covering may be readily applied to and securely interlocked with the outer portion of the eyelet; and it consists in the 15 improvements which I will now proceed to describe and claim.

Of the accompanying drawings, forming a part of this specification, Figure 1 represents a perspective view of an eyelet embodying 20 my invention. Fig. 2 represents a sectional view of the same. Fig. 3 represents a sectional view showing the plastic covering applied to the flange or outer end of the eyelet. Fig. 4 represents a sectional view showing a 25 somewhat different form of eyelet.

The same letters of reference indicate the same parts in all the figures.

In carrying out my invention I construct an eyelet having a tubular portion or barrel a , 30 an outwardly-inclined or frusto-conical flange a' at one end of the eyelet, said flange joining the body of the eyelet at an obtuse angle a^2 , and spurs a^3 formed on the upper or outer edge of the flange a' and bent downwardly 35 from said flange, so that their lower ends are substantially on a level with the angle a^2 , formed by the intersection of the body a and flange a' of the eyelet.

The eyelet above described is placed upon 40 a die-plate having a cavity formed to receive the barrel or body a and fit closely the exterior of the same. The lower portion of the flange is caused by the angle at which it joins the body of the flange to rest squarely upon the die-plate, so that the downward pressure 45 applied, as hereinafter described, to the flange in the operation of applying the head thereto will not crowd or wedge the flange into the cavity of the die-plate. The spurs a^3 being 50 on a level with the angle a^2 bear upon the upper surface of the die-plate and support

the upper edge of the flange during the covering operation, said spurs preventing the flange from yielding downwardly and becoming flattened against the die-plate. The spurs 55 are preferably separated by intervals of considerable length, as shown in Fig. 1, so that portions of the edge of the flange are presented between the spurs as cutting-edges, which readily cut into the mass of covering 60 material which is pressed downwardly upon the flange.

The covering material is preferably cut out in the form of an annular blank and is placed upon the upper edge of the flange and pressed 65 downwardly thereupon by means of a suitable die formed to enter the body of the eyelet and to mold the plastic material into an annular covering b of substantially the form shown in Fig. 3. The raised cutting-edge of 70 the flange, supported as described by the spurs a^3 , partially divides the mass of covering material, causing the outer portion of said mass to flow downwardly and inwardly and cover the outer surface of the flange, the spaces between the spurs enabling the covering material 75 to readily find its way to all parts of the outer surface of the flange, the said material entering the spaces behind the spurs, so that the covering is interlocked with the flange 80 not only by the overhang of the flange, but by the engagement of the covering with the spurs.

In Fig. 4 I show a shoulder a^4 formed at the junction of the flange with the body of the eyelet, said shoulder being the equivalent of 85 the angle a^2 and affording more extended support for the flange than said angle.

I claim—

1. An eyelet comprising a tubular body, a frusto-conical flange formed on one end of said body and inclined outwardly and upwardly therefrom, and a series of spurs projecting downwardly from the outer and upper edge of said flange, as set forth.

2. An eyelet comprising a tubular body, a frusto-conical flange formed on one end of said body and inclined outwardly and upwardly therefrom, a series of spurs projecting downwardly from the outer and upper edge of said flange, and a covering of plastic material 95 molded upon said flange, said covering being applied to both the outer and inner sides of

the flange and interlocked with the spurs thereof.

3. An eyelet comprising a tubular body, and a frusto-conical flange formed on one end of the body and inclined upwardly and outwardly therefrom, said flange having supports at its lower and upper edges adapted to bear upon a die-plate, as set forth.

In testimony whereof I have signed my name to this specification, in the presence of two subscribing witnesses, this 8th day of August, A. D. 1895.

ELEAZER KEMPSHALL.
